UNITED STATES PATENT OFFICE.

JOHN H. CRIST AND JOHN C. SCHILKEN, OF PITTSBURGH, PENNSYLVANIA.

ADJUSTABLE BRACKET.

1,231,000.

Specification of Letters Patent. Patented June 26, 1917.

Application filed May 1, 1916. Serial No. 94,531.

To all whom it may concern:

Be it known that we, JOHN H. CRIST and JOHN C. SCHILKEN, citizens of the United States, residing at Pittsburgh, in the county 5 of Allegheny and State of Pennsylvania, have invented certain new and useful Improvements in Adjustable Brackets, of which the following is a specification.

Our invention consists of an improvement 10 in adjustable brackets adapted to be used in connection with a suitable wall or other supporting structure, or a supporting column or backing of any suitable kind, for carrying or supporting any desired object for display, or

15 any purpose to which the device may be put. One of the particular objects in view is to provide, in a bracket of the type herein set forth, a simple, cheap and efficient construction, capable of being quickly adjusted to 20 any desired position, and there located by mere adjustment or movement of the bracket member itself. It constitutes an improvement on that form of bracket construction disclosed in the prior application of John 25 H. Crist, filed March 1, 1915, Serial No. 25143.

It comprises, generally stated, a supporting column or bar capable of attachment to any desired base or wall or the like provided 30 with a slotted front, and a bracket having a locking member slidably mounted therein and pivotally connected with the bracket itself in such a manner as to utilize the pivoting extremity of the bracket as a cam lock 35 capable of being tightened or loosened, the parts being connected as a unit by the pivotal mounting of the bracket, as hereinafter more fully described.

Preferred forms of the invention are 40 shown in the accompanying drawings, in which—

Figure 1 is a vertical sectional view showing one form of the invention as applied to the slotted front plate of a supporting column.

Fig. 2 is a face view of a portion of such slotted front column support.

Fig. 3 is a sectional plan view of Fig. 1, indicated by the line III. III. of Fig. 1.

50 Fig. 4 is a perspective detail view showing the operative mechanism of the bracket of Fig. 1.

Fig. 5 is a collective detail view showing the parts of the locking and supporting 55 mechanism detached in perspective.

Fig. 6 is a detail view showing a modified construction of bracket supporting plate.

Fig. 7 is a view similar to Fig. 4, but showing a modified construction of bracket having a supplemental brace support. 60

Fig. 8 is a sectional detail view similar to Fig. 3, showing a modified construction.

For the purpose of providing a continuous slotted attaching means for the bracket, or for any desired number of brackets, we 65 utilize a casing 14 of sheet metal, adapted to conform generally to the cross section of an interior supporting bar 38, which may be of any preferred form, as a standard channel form, as shown.

70 Casing 14 may be made to completely embrace the supporting bar, as shown in Fig. 3, or may be attached to it in any other suitable way, but is so constructed as to provide the laterally extending lip sections 15, 15, at each side of an interior cavity 16, and providing an intervening slot 17 for attachment of the bracket holding member. It will of course be understood that the casing 14 may be made of any suitable form to provide the interior clearance opening and the inwardly turned retaining lips with the intervening slot, and that the casing may be made and used quite independent of the interior supporting bar, as desired. 75

80 Said bracket holding member, as shown, consists of a plate 18 of a cross sectional width and thickness to freely fit and slide within the longitudinal cavity 16 behind the retaining lip or flange portions 15, against 85 which it bears outwardly in tightened position.

90 Plate 18 is of a sufficient length to insure the tightening action, hereinafter described, in case its inner terminal portion is thrust 95 against the front face of bar 38.

Plate 18 is provided at one end with an outwardly bent narrowed pivoting terminal 19, of a width to freely extend through the slot 17 between the edges of lips 15, and is 100 provided with a terminal pivoting hole 20.

Bracket 21, which may be of a strip of plate metal, or a wire flattened at its pivoted end, or of any other suitable construction, is pivotally connected with terminal 105 19 by a pivoting rivet or screw 26, passing through a similar hole 20.

Between the inner end of the bracket 21 and the outer face of flange lips 15, and bearing thereagainst slidably, is a washer 110

plate 22 having a slot 23 adapted to fit over the abutment 19 when the parts are assembled.

The pivoting end of the bracket 21 is 5 rounded at one side of its longitudinal center, inwardly beyond the pivotal mounting 26, as indicated at 25, whereby to provide a locking cam face, the distance from the pivoting center to the inner abutting straight 10 portion 27 being just sufficient to provide for a tight intimate binding engagement when the bracket is thrust outwardly in alignment with the abutment terminal 19, as indicated in Fig. 3. The distance from the 15 pivoting center to such bearing end 27 is slightly greater than the distance between the pivoting center and the straight side 28 of the bracket, into which the curved portion 25 merges, so that when the bracket 20 is thrust around to the position indicated in dotted lines in Fig. 3, it will insure loosening of the device, so that it may be easily raised or lowered to any desired position or entirely removed from the slotted cavity 25 endwise, as will be readily understood.

When located at the desired height, and the bracket 21 is thrust around into operative position, the cam terminal bearing against the outer face of plate 22 thrusts it 30 tightly against the outer face of flange lips 15, at the same time drawing abutment 19 outwardly and bringing the outer face of plate 18 into tight gripping engagement with the inner sides of the flange lips. 35 When thus adjusted, the bracket is fixedly held in position and may be used to support any article or articles within its capacity as to weight.

If desired, the bracket supporting plate 40 may be made in the manner shown in Fig. 6, in which plate 18^a is connected with terminal 19^a by a narrowed neck providing the shouldered slots 29^a, 29^a, and the pivoting hole 20^a. In such case the washer plate 22 45 fits by its slot 23 over and into such slots, slot 23 being sufficiently wide, and by intervening between the front shoulders of terminal 19^a and the lips 15, provides a positive limiting or holding washer, insuring 50 maintenance of the parts in operative position.

If desired, the bracket may be made in the form illustrated in Fig. 7, similar to the bracket shown in Fig. 1 of the application 55 above referred to, in which case the upper bracket member 21^a may be formed at its outer end in any suitable manner, as indicated, reversed upon itself, providing the diagonal brace 21^b, each of which portions 60 is provided at its inner end with a pivoting terminal of the same construction as of the single form above described.

The plate 18^a in such case is provided with an upper and a lower abutment 19^a, 65 each of which is pivotally connected at 26^a,

with each inner end of the bracket members, each of which is provided at one side with the curved cam terminal formation.

The washer plate 22^a is likewise provided with a slot 23^a at each end portion for passage of the abutment 19^a, and the construction as thus made operates in exactly the same manner as above described, except that it is considerably stronger and more rigid, due to the duplication of the pivoting mem- 75 bers.

In Fig. 8 we show a further modification in which the bracket arm 21^c is equidistant at its pivotal terminal as to the distance between the pivoting center and the end and 80 one of its sides respectively, whereby to provide a double cam face 27^c, 27^c, respectively, intervening clearance being provided by cutting away the metal somewhat less than the arc of the circle from the pivoting center, 85 as indicated at 25^c.

The other elements are similarly constructed and indicated by similar numerals having the exponent "c."

The construction and operation of the de- 90 vice will be readily understood from the foregoing description, and it will also be understood that the shape or design of the bracket itself may be variously changed or adapted to the various uses to which the 95 invention may be applied.

It will be understood also that the supporting bar 38 may be furnished with any suitable attaching terminals or connections, such as those shown in the above mentioned 100 application, whereby to adapt it to utilization dependent on the local conditions, as for instance, by attachment to the ceiling and floor respectively, or other means may be provided for securing it against a wall, 105 column or the like.

The invention is well adapted to various uses, and may be made in different sizes and weights, or otherwise changed or varied, depending on the use to which it is put. 110

What we claim is:

1. The combination with a supporting standard having a longitudinal slotted cavity, of a mounting device slidably engaging said slotted cavity, said device comprising 115 a supporting plate slidably mounted therein, a pivoting terminal thereon and extending outwardly through said slot in said standard, a washer plate slidably mounted on said terminal, and a bracket pivoted to said 120 terminal having a rigid tightening cam portion adapted to bear against the outside face of the washer plate and to tighten the supporting plate against the inside thereof.

2. The combination with a supporting 125 standard having a longitudinal slotted cavity, of a mounting device slidably engaging said slotted cavity, said device comprising a supporting plate slidably mounted therein, a pivoting terminal formed integral therewith 130

and extending outwardly at right angles to said plate through said slot in said standard, a washer plate slidably mounted on said terminal, and a bracket pivoted to said terminal, having a rigid tightening cam portion adapted to bear against the outside face of the washer plate and to tighten the supporting plate against the inside thereof.

In testimony whereof we hereunto affix our signatures in the presence of two witnesses.

JOHN H. CRIST.
JOHN C. SCHILKEN.
